UNITED STATES PATENT OFFICE

CHARLES S. BAKER, OF CORNING, NEW YORK, ASSIGNOR TO INGERSOLL-RAND COMPANY, OF JERSEY CITY, NEW JERSEY, A CORPORATION OF NEW JERSEY

COOLING DEVICE

Application filed May 24, 1929. Serial No. 365,653.

This invention relates to portable compressors, but more particularly to a cooling device for cooling the pressure fluid during its passage from the receiver tank to the mechanism it is adapted to actuate.

One object of the invention is to maintain the pressure fluid at a sufficiently low temperature so that it will have no injurious effect on the hose through which it flows to the mechanism intended to be actuated.

Other objects are to simplify the construction and reduce the cost of devices of this character and to obtain these advantages without adding materially to the weight of the compressor.

Other objects will be in part obvious and in part pointed out hereinafter.

In the drawings illustrating the invention and one form which it may assume in practice,

Figure 1 is a side elevation of a portion of a portable compressor equipped with a cooling device constructed in accordance with the practice of the invention, and

Figure 2 is a transverse view taken through Figure 1 on the line 2—2 looking in the direction indicated by the arrows.

Referring to the drawings, A designates a compressor mounted on a vehicle B and having a discharge pipe C through which the compressed fluid flows into a receiver tank D mounted on the vehicle B.

The prime mover for actuating the compressor A may consist of an internal combustion engine (not shown) but which may be mounted in driving relationship with the compressor A on the vehicle B in the usual manner. The compressor is accordingly provided with a fuel tank E disposed in this instance above the receiver tank D whereby it is supported.

Interposed between the tanks D and E are brackets F comprising an upper section G and a lower section H. The sections G and H are provided with surfaces J and K curved to conform to the curvature of the tanks E and D respectively. The sections G and H are further provided with lateral flanges L and O respectively for the reception of means to clamp the sections together. In the pres-

ent instance this is accomplished by rods P having curved portions Q which overlie the tank E, and straight portions R extending through the flanges L and O. The rods are threaded at their ends to receive nuts S whereby the sections L and O are drawn together and the tank E is secured fixedly to the section G.

The tank E and the sections G and H are held in proper position by rods T threaded at their ends. The uppermost ends U of the rods T extend through the flanges L and O and are provided with nuts V which seat on the flanges L. The opposite ends of the rods T extend through flanges W of a main frame X and are provided with nuts Y to draw the brackets F firmly on the tank D and thus also secure the said tank firmly in position on the main frame X.

As may be observed, the receiver tank D is of relatively small proportions, in order to maintain the weight of the apparatus to a minimum. In this respect portable compressors differ from stationary compressors. In the latter type the limitation of weight is seldom a desideratum. The receiver tanks may be of large proportions and consequently a large area of surface will be exposed to the atmosphere. This enables the heat of compression to be readily dissipated. In portable compressors, however, in which receiver tanks of small size are used practically all of the heat created by compression is retained by the pressure fluid. In the absence of suitable cooling means this heat is carried to the hose line leading to the machine intended to be actuated, and, since the hose lines usually consist of rubber or other material upon which heat has an adverse affect, the life of the hose is of short duration.

The present invention aims to reduce the temperature of the pressure fluid flowing from the receiver tank to the hose. To this end the receiver tank D is provided with an after-cooler Z in the form of a coiled pipe, one end of which is connected to the receiver tank D as at b and carries at its other end a manifold c to which a hose line or lines d may be connected. Preferably the after-cooler Z consists of a plurality of pipe sections e ar-

ranged in parallelism and connected at their ends by suitable couplings *f*.

The after-cooler *Z* is preferably disposed between the bracket sections *G* and *H*. When so arranged the bracket sections *G* and *H* may be provided with grooves *g* and *h* respectively in the opposed surfaces of the sections and spaced relatively to each other to conform to the spacing of the pipe sections *e* which they are adapted to receive. In depth the grooves *g* and *h* may be somewhat less than the radius of the pipe sections *e* so that when the brackets *G* and *H* are drawn together the pressure applied for this purpose will act on the pipe sections *e* instead of permitting the adjacent surfaces of the bracket sections to contact. In this way the after-cooler will be rigidly secured in the assembled position unaffected by the vibration.

20 In the operation of the device the air compressed by the compressor *A* will flow through the discharge pipe *C* into the receiver tank *D*. From thence the compressed air will flow through the pipe sections *e* to the manifold *c* and, since practically the entire exterior surfaces of the pipe sections *e* are exposed to the atmosphere, the heat of compression carried by the pressure fluid will be dissipated to such an extent that 25 when the pressure fluid reaches the hose line *d* it will be reduced to a temperature at which it may be safely conveyed through the hose line without danger of causing injury thereto.

30 35 In practice the device has been found to function in an entirely satisfactory manner. It may be readily applied to existing compressors without necessitating expensive alterations to the compressor and also without adding materially to the weight of the apparatus.

I claim:

1. In a cooling device for portable compressors, the combination of a compressor and a receiver tank, a fuel tank supported by the receiver tank, a coiled pipe between the tanks and connected to the receiver tank, said coiled pipe being exposed to the atmosphere to cool the pressure fluid flowing there- 45 through, and a bracket on the receiver tank to support the fuel tank and the coiled pipe, said bracket comprising a pair of sections adapted to clamp the pipe therebetween.

2. In a cooling device for portable compressors, the combination of a compressor and a receiver tank, a fuel tank, a coiled pipe connected to the receiver tank and exposed to the atmosphere to cool the pressure fluid flowing from the receiver tank, a plurality 50 of brackets, each comprising a pair of sections interposed between the tanks to support the fuel tank and having grooves to receive the coils of the pipe, and means for clamping the sections together and to clamp the coiled pipe between the sections.

3. In a cooling device for portable compressors, the combination of a compressor and a receiver tank, a fuel tank, a pipe connected to the receiver tank and coiled between the tanks and exposed to the atmosphere to cool the pressure fluid flowing from the receiver tank, a plurality of brackets, each comprising a pair of sections disposed between the tanks to support the fuel tank, grooves in the opposed surfaces of the sections adapted to receive the coils of the pipe, and means for clamping the sections together and to clamp the pipe between the sections. 70 75

4. In a cooling device for portable compressors, the combination of a compressor and a supporting frame therefor, a receiver tank for the compressor, a coiled pipe connected to the receiver tank and exposed to the atmosphere for cooling of fluid compressed by the compressor, and means for rigidly securing the pipe to the frame whereby said pipe is supported, said means engaging each coil of the pipe to prevent relative movement of said coils. 80 85

5. In a cooling device for portable compressors, the combination of a compressor and a supporting frame therefor, a receiver tank for the compressor mounted on the frame, a coiled pipe connected to the receiver tank and exposed to the atmosphere for cooling of fluid compressed by the compressor, a bracket mounted on the receiver tank and forming a support for said pipe, and bolts for connecting the bracket to the frame, said bolts being disposed on opposite sides of the receiver tank to clamp the receiver tank to the frame. 90 95 100

6. In a cooling device for portable compressors, the combination of a compressor and a supporting frame therefor, a receiver tank for the compressor, a coiled pipe connected to the receiver tank for cooling of fluid compressed by the compressor, a bracket comprising a pair of sections adapted to receive the pipe therebetween, means for drawing the sections together to thereby secure the pipe in the bracket, and means for securing said bracket to the frame. 105 110

7. In a cooling device for portable compressors, the combination of a compressor and a supporting frame therefor, a receiver tank for the compressor, a pipe connected to the receiver tank and forming a portion of a conduit for conveying pressure fluid from the receiver to a machine intended to be actuated, said pipe comprising a plurality of parallelly arranged straight sections and elbow sections connecting the ends of adjacent sections to form a continuous path for the pressure fluid through said pipe, and a bracket engaging the sections of the pipe and being rigidly connected to the frame for supporting the pipe. 115 120 125

8. In a cooling device for portable com- 130

pressors, the combination of a compressor and a supporting frame therefor, a receiver tank for the compressor, a pipe connected to the receiver tank and exposed to the atmosphere for cooling the pressure fluid flowing therethrough, said pipe comprising a plurality of parallelly arranged straight sections and elbow sections connecting the ends of adjacent straight sections to form a continuous path for the pressure fluid through said pipe, a bracket comprising a pair of members disposed on opposite sides of the sections, means for drawing the members together to clamp the sections between the members, means for securing the bracket to the frame, and additional means on the members to prevent relative movement of the sections.

In testimony whereof I have signed this
specification.

CHARLES S. BAKER.
